Primary Examiner — Austin Murphy

CLAIM

The ornamental design for the electronic panel with fingerprint, as shown and described.

DESCRIPTION

FIG. 1 is a top plan view of the electronic panel with fingerprint showing my new design;

FIG. 2 is a bottom plan view thereof;

FIG. 3 is a right side plan view thereof;

FIG. 4 is a left side plan view thereof;

FIG. 5 is a front plan view thereof;

FIG. 6 is a rear plan view thereof; and,

FIG. 7 is a front perspective view thereof.
